UNITED STATES PATENT OFFICE.

BRONISLAW JANUSZCZAK, OF POINT ST. CHARLES, MONTREAL, QUEBEC, CANADA.

GRIPPING-TOOL.

1,191,702.

Specification of Letters Patent. Patented July 18, 1916.

Application filed June 11, 1915. Serial No. 33,611.

To all whom it may concern:

Be it known that I, BRONISLAW JANUSZCZAK, a subject of the King of Great Britain, and residing in Point St. Charles, 5 in the city of Montreal, Quebec, Canada, have invented certain new and useful Improvements in Gripping-Tools; and I do hereby declare that the following is a full, clear, and exact description of the same.

10 The invention relates to improvements in a "gripping tool" and its object is to devise an instrument whereby it will be possible to reach bottles or the like when on a shelf that is too high and not accessible otherwise 15 than by raising a foot ladder.

The invention consists in a rod of convenient length provided at one of its ends with a jaw like member otherwise called the gripping member actuated by means of 20 a lever and held in a closed position by a strong spring.

In the drawings Figure 1 is a side elevation of the invention. Fig. 2 is a plan view showing the jaws closed. Fig. 3 is a plan 25 view showing the jaws opened.

Like numerals of reference indicate corresponding parts in each figure.

Referring to the drawings, 1 is a handle or rod of any suitable length, size and material.

3 is a cap embracing the end of the handle 1 and rigidly secured thereto, said cap having the projecting arm 3^a, the outward end of which is slightly enlarged and 35 has the bolt hole 4.

5 is a plate secured to the handle 1, having the hand-lever 6 pivotally secured at 7.

8 is a bracket rigidly secured to the handle 1 and 9 is a lever fulcrumed at 10, one end 40 of said lever having lateral projecting pins 11 and the other end is pivotally secured to one end of the rod 12, the other end of said rod being pivotally connected to the end of the hand-lever 6.

45 13 are loops having the projecting flanges 14 which are provided with holes 15, said loops being so arranged as to engage the projecting pins 11.

16 and 17 are rods pivotally secured at one 50 end between the flanges 14 by means of the bolt 18 which passes through the holes 15.

19 and 20 are jaws each semi-elliptical and having projecting therefrom the members or arms 21 and 22, which are pivotally 55 secured to the ends of the connecting rods 16

and 17 by means of the bolts 23 and 24, each of said jaw members being pivoted intermediate of their length to the projecting arm 3 by means of the bolt 25, thus forming scissors-like gripping members which 60 are covered with any suitable material to prevent the articles that are gripped from slipping. A rubber cap 26 is preferably used.

27 is a coil spring secured at one end to 65 the bolt 23 and at the other end to the bolt 24.

In the operation of the invention, the hand-lever 6 which is secured at the lower end of the handle 1 is pressed down thereby 70 actuating the lever 9 fulcrumed at 10 by means of the rod 12. The projecting pins 11 on the end of the lever 9 engage the loops 13 when tipped over, pull the arm or rod 16 and 17 forward, thereby effecting a spread 75 out motion of the jaw members 19 and 20. When the hand-lever 6 is released, the coil spring 27 pulls the jaw members 19 and 20 together, which form a substantial gripping member sufficiently strong to hold a bottle 80 or a box.

A feature of the invention is that in stores, one may dispense with the usual foot ladder which is generally used, and use a device such as herein described, thus saving valuable time.

What I claim is:—

A device of the character described, comprising a pole, a cap thereon provided with an arm, a pair of crossed pivotally connected 90 arms terminating in coöperating jaws and fulcrumed on the arm of the aforesaid cap, rods pivotally connected to said pivotally connected arms at one end, the other end of said rods being pivotally connected together, 95 loops pivotally connected on the pivotal connection of said rods, a bell crank lever carried by said pole near its upper end and provided with outwardly projecting pins adapted to engage the aforesaid loops, an 100 elbow lever fulcrumed on said pole, connections between said levers and a spring secured to the pins of the pivotal connections of the arms and rods.

Signed at Montreal, Quebec, Canada, this 105 fifth day of March, 1915.

BRONISLAW JANUSZCZAK.
